ARTICLE FOR RELIGIOUS USE

Raymond F. Brennan, Attleboro, Mass.

Application November 13, 1942, Serial No. 465,512

6 Claims.

(Cl. 41—10)

This invention relates to an article adapted for religious use which is in the nature of a rosary plaque.

With the considerable number of men now serving in the armed forces and the difficulty experienced in obtaining beads of the character heretofore used in rosaries, the present construction is designed to provide a religious article which may serve as a substitute for rosaries, and which is capable of being carried on the person and employed as the usual rosary.

One object of the invention is the provision of a plaque which may be molded or otherwise shaped and provided with front and rear side faces having portions corresponding with parts of a rosary which are raised from or embossed upon opposite side faces of the plaque in such a manner as to be continuous throughout the opposite side faces.

Another object of the invention is to provide a device of this character having the religious symbols displayed in raised relief upon opposite sides thereof so that the user may locate the parts readily by touch and identify them.

Another object of the invention is to provide a device of this character having a display face formed thereon with religious symbols which may constitute parts of a rosary embossed in raised relief thereon, so as to be capable of being readily identified and distinguished from each other by touch.

Other objects and advantages of the invention relate to various novel details of the construction and arrangement of the parts as will be more fully set forth hereinafter.

Referring to the drawings—

Fig. 1 is a front elevational view of the plaque, Fig. 2 is a rear elevational view of the same,

Fig. 3 is a vertical sectional view, taken substantially along the lines 3—3 of Figs. 1 and 2,

Fig. 4 is a horizontal sectional view, taken substantially along the lines 4—4 of Figs. 1 and 2,

Fig. 5 is a detail sectional view showing one of the beads 9 in elevation and with the top surface thereof roughened to make it more readily identified by touch, and,

Fig. 6 is a detail sectional view showing one of the beads 9 in elevation with the top thereof pointed to make it readily identified by touch.

In the embodiment of the invention illustrated herein 1 designates the plaque which may be cast, molded or otherwise formed from any suitable metal, plastic or composition material to provide front and rear display faces indicated respectively by the reference characters 2 and 3.

The front face 2 of the plaque carries a scroll

4 in partial relief and has a raised border frame 5 extending about the side and end edges thereof. A similar raised border frame 6 is carried by the rear face 3 of the plaque and extends about the side and end edges thereof.

Mounted upon the front face 2 of the plaque is a cross 8, from which there extends a bead 9 of comparatively large diameter and three beads 10 of smaller diameter followed by a second large bead 9 located closely adjacent to the upper end portion of the plaque. All of these rosary elements are embossed upon the front face 2 of the plaque so that substantial portions of each of them are raised above the general level of the front face to a degree sufficient to permit their location and identification readily by touch. Each succeeding rosary element is connected to those upon opposite sides thereof by links 12, which are also embossed upon the face of the plaque and raised slightly from the general level thereof.

A connecting link 14, similar to the connecting links 12, extends from the second large bead 9 located adjacent to the top of the front face 2 of the plaque over the end surface 15 of the plaque, to connect the large bead 9 with a medal or bead 16 shown as positioned adjacent to the upper edge portion of the rear face 3 of the plaque, as is usual in the arrangement of the elements in rosary construction.

On the rear face 3 of the plaque and from one side of the medal 16 extends a series of ten small beads 10, followed by a large bead 9, and so on through five decades of small beads, the final small bead of the fifth decade being connected to that side of the medal 16 opposite to that to which the initial bead 10 of the first decade was connected.

Each of the large and small beads on the rear face 3 of the plaque is embossed thereon in raised relation with the general level of the rear face 3 of the plaque, and successively adjacent beads are connected by links 12 which are embossed upon the surface of the plaque in raised relation with its general level.

The top surface of the large beads 9 may be knurled, roughened or striated to render them more readily identified by touch, as is indicated at 20, or these beads may have the top surfaces drawn upward to a point or otherwise shaped as indicated at 21, to distinguish them readily from the decade beads 10.

When used as a rosary the same procedure may be followed as with a rosary, starting from the cross 8 to the first "Our Father" bead 9, then the three "Hail Mary" beads 10, to the second "Our Father" bead 9, and to medal 16, and from medal

16 through each of the five decades of "Hail Mary" beads 90 with the intermediately positioned "Our Father" beads 9, back to the medal 16.

The various beads or religious symbols are all arranged in the order of succession in which they are present in a rosary, and each is raised sufficiently from the general level of the plaque surface to permit its location and identification by touch so that the several symbols may be followed by the user in the order in which they occur in a rosary.

While in the present construction, the plaque-like shape is flat and formed to provide front and rear display faces for the reception of religious symbols, it is to be understood that the invention comprehends the use of a single display face, which may have a plane or curved surface, as well as a shape provided with plural display faces so positioned relative to each other as to permit the application thereto of religious symbols in a continuous order of succession by having the same embossed in raised relief thereon.

What I claim is:

1. An article for religious use provided with a display face having religious symbols constituting elements of a rosary in raised relief thereon and arranged with symbols of uniform size disposed in groups of a number conforming to the number in the groups occurring in a rosary with symbols of different size intervening between the groups whereby said groups may be located and identified by the sense of touch.

2. An article for religious use in the form of a plaque provided with opposed display faces having continuously connected religious symbols arranged in a definite order of succession embossed in raised relief thereon to permit of their identification by touch, said symbols extending in

sequential order from one to the other of said display faces.

3. An article for religious use provided with opposed display faces having embossed in raised relief thereon elements of a rosary including small and large beads arranged in the order in which they occur in a rosary, and embossed connections connecting adjacently positioned embossed beads.

4. An article of the character described adapted for religious use provided with a display face having a plurality of religious symbols constituting elements of a rosary embossed in raised relief thereon, the exposed faces of certain of said embossed religious symbols being modified to distinguish them from other similar embossed symbols through the sense of touch.

5. An article of the character described provided with opposed display faces having elements of a rosary embossed in raised relief thereon and extending from one to the other of said display faces and throughout each display face in the order of succession in which they occur in a rosary whereby the elements may be located and identified successively throughout by the sense of touch.

6. An article of the character described provided with adjacently positioned display faces having a connected series of religious symbols embossed in raised relief thereon and extending throughout each display face and from one to the other of said faces in a definite order of succession whereby the user may follow the said embossed symbols in their order of succession and distinguish each from the other through the sense of touch.

RAYMOND F. BRENNAN.
